CLAIM

I claim the ornamental design for a dog leash, as shown and described.

DESCRIPTION

FIG. 1 is a perspective view of a dog leash in a closed position showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

(Continued)

FIG. 8 is a perspective view of the dog leash in an extended position.

1 Claim, 8 Drawing Sheets
